(57) **CLAIM**

The ornamental design for a cushion for medical instrument stand, as shown and described.

DESCRIPTION

FIG. 1 is a top, right perspective view of a cushion for medical instrument stand in a state of use;

FIG. 2 is a top, right perspective view of the cushion for medical instrument stand without showing the stand;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The dashed lines shown in FIG. 1 depict environmental subject matter and form no part of the claimed design. The dash line shown in FIG. 6 and the area bounded by the dash line and the solid lines depict portions of the cushion for medical instrument stand that form no part of the claimed design. The dash-dot-dash lines in FIG. 6 depict the boundaries of the claim and form no part thereof.

1 Claim, 4 Drawing Sheets
